(57) **CLAIM**

The ornamental design for an article display, as shown and described.

DESCRIPTION

FIG. 1 is a perspective view of an article display, embodying our new design;

FIG. 2 is a front elevational view of the article display of FIG. 1;

FIG. 3 is a side elevational view of the article display of FIG. 1 wherein the other side elevational view is a mirror image; FIG. 4 is a back elevational view of the article display of FIG. 1;

FIG. 5 is a top view of the article display of FIG. 1;

FIG. 6 is a bottom view of the article display of FIG. 1;

FIG. 7 is a perspective view of an article display, embodying an embodiment of our new design;

FIG. 8 is a front elevational view of the article display of FIG. 7;

FIG. 9 is a side elevational view of the article display of FIG. 7 wherein the other side elevational view is a mirror image;

FIG. 10 is a back elevational view of the article display of FIG. 7;

FIG. 11 is a top view of the article display of FIG. 7;

FIG. 12 is a bottom view of the article display of FIG. 7; FIG. 13 is a perspective view of an article display, embodying an embodiment of our new design; FIG. 14 is a front elevational view of the article display of FIG. 13; and FIG. 15 is a side elevational view of the article display of FIG. 13 wherein the other side elevational view is a mirror image; FIG. 16 is a back elevational view of the article display of FIG. 13; FIG. 17 is a top view of the article display of FIG. 13; FIG. 18 is a bottom view of the article display of FIG. 13; FIG. 19 is a perspective view of an article display, embodying an embodiment of our new design; FIG. 20 is a front elevational view of the article display FIG. 19; FIG. 21 is a side elevational view of the article display of FIG. 19 wherein the other side elevational view is a mirror image; FIG. 22 is a back elevational view of the article display of FIG. 19; FIG. 23 is a top view of the article display of FIG. 19; FIG. 24 is a bottom view of the article display of FIG. 19; FIG. 25 is a perspective view of an article display, embodying an embodiment of our new design; FIG. 26 is a front elevational view of the article display of FIG. 25; FIG. 27 is a side elevational view of the article display of FIG. 25 wherein the other side elevational view is a mirror image; FIG. 28 is a back elevational view of the article display of FIG. 25;

FIG. 29 is a top view of the article display of FIG. 25; FIG. 30 is a bottom view of the article display of FIG. 25; FIG. 31 is a perspective view of an article display, embodying an embodiment of our new design; FIG. 32 is a front elevational view of the article display of FIG. 31; FIG. 33 is a side elevational view of the article display of FIG. 31 wherein the other side elevational view is a mirror image; FIG. 34 is a back elevational view of the article display of FIG. 31; FIG. 35 is a top view of the article display of FIG. 31; FIG. 36 is a bottom view of the article display of FIG. 31; FIG. 37 is a perspective view of an article display, embodying an embodiment of our new design; FIG. 38 is a front elevational view of the article display of FIG. 37; FIG. 39 is a side elevational view of the article display of FIG. 37; FIG. 40 is a back elevational view of the article display of FIG. 37; FIG. 41 is a top view of the article display of FIG. 37; FIG. 42 is a bottom view of the article display of FIG. 37; and, FIG. 43 is a side elevational view of the article display of FIG. 38, embodying an embodiment of our new design. The broken lines shown in the drawings are for illustrative purposes only and form no part of the claimed design.
